UNITED STATES PATENT OFFICE.

HENRY A. ROBERTS, OF BOSTON, MASSACHUSETTS.

IMPROVED REFRIGERATOR.

Specification forming part of Letters Patent No. 77,098, dated April 21, 1865.

To all whom it may concern:

Be it known that I, HENRY A. ROBERTS, of Boston, county of Suffolk, and State of Massachusetts, have invented certain new and useful Improvements in the Manufacture of Refrigerators; and to enable others skilled in the art to make and use the same, I will proceed to describe it by referring to the drawings, in which the same letters indicate like parts in each of the figures.

The nature of this invention consists in constructing a refrigerator and provision-safe of two or more sections or chambers fitting vertically one upon the other in such a manner that the sections can be easily and readily adjusted so as to increase or diminish its interior size or capacity, the said construction having upper and lower rims and inner and outer walls made of metal or other suitable material, either bolted, hermetically sealed, or soldered together so as to form an air-tight vacuum, each section being removable and adjustable; so, if there is not a sufficient quantity of articles to be refrigerated to occupy the full capacity of any one section or chamber, that section can be divided, cut off, or removed, and reinstated at pleasure by first lifting or removing the cooling-chamber, then removing the division or unneeded section, and reinstating the cooling-chamber upon the remaining section or chambers that contain the materials for refrigeration. By this arrangement I reduce or diminish the capacity of the chamber wholly in accordance with the quantity of materials to be refrigerated. Thus it will be seen that I reduce materially the consumption of ice, as I diminish the capacity of the refrigerating-chamber and obtain a result of economy which has never before been accomplished.

The nature of this invention further consists of the formation of a frame or a series of frames conforming to the shape of the interior construction of the refrigerator, so as to occupy all, or nearly all, of the interior circumference of the refrigerator. Said frame or frames have an outer rim, with intersecting rims extending from one side to the other, thus forming between the rims open spaces, and into each space thus formed is placed a receptacle or receptacles so constructed as to occupy and utilize each and every space. It will be seen that by this arrangement I do

away with the ordinary refrigerator-shelves, and in their stead I adopt the receptacles as described for holding and containing the articles intended for refrigeration, and said receptacles, by their formation, do utilize the room within the refrigerator, thus doing away with placing different domestic articles or utensils—such as an earthen pitcher, or a plate, or pail, or can, &c.—for holding food within the refrigerator, which monopolizes the room to disadvantage. By utilizing the room of a refrigerating-chamber, as by my invention, I am enabled to produce a structure of increased capacity and utility, and with great economy in the use of ice, and occupying but half of the space of the ordinary refrigerator.

The nature of this invention further consists in constructing an ice-receptacle which of itself is perfectly air-tight, movable and adjustable at pleasure, consisting of vertical flue or a series of vertical flues provided with open apertures at the top and bottom relatively to an intersecting horizontal flue having discharging-orifices for both circulating currents of air and the products of atmospheric condensation. When the same is arranged with a frigorific chamber, producing results of refrigeration by means of internal continuous circulation of currents of air, the outer walls of which are perforated and covered with fibrous or evaporating substance, through which a flue or series of flues are arranged in any desirable position, either vertical or horizontal, and provided for circulation and condensation of air, partially to protect the walls from contact with the ice. These flues are provided with radial conductors to increase the cooling and condensing surface therein. At the outer edge, and joining the bottom of this ice-receptacle, is provided a fluid-cup, for the purpose of supplying the evaporating or fibrous surface with fluid, which renders it air-tight and presents a surface for evaporation. Near the top edge of this cup is provided a discharge-tube for the escape of surplus fluid. A good result of refrigeration can be produced by constructing this ice-box perfectly air-tight, with or without the use of the evaporating material or surface, by simply having one discharge-orifice from said box into the cup *p*; but it is believed that far greater and more successful results will be obtained by the use of perforated sides with fibrous material covering.

The nature of this invention further consists in the mode of manufacture, whereby I am enabled to construct a refrigerator with its receptacles of any desirable form or shape adapted for the trade or use.

The object desired to be attained thereby is to increase the rapidity of and cheapen the manufacture and render the articles more perfect and desirable for transportation and use.

It will be observed that by the construction of a refrigerator as above described, it will produce an internal circulation of cool dry air, thus preventing a provocation of mold, which will invariably take place where moisture exists.

In the accompanying drawings, Figure 1 is a vertical section elevation of this refrigerator. Fig. 2 is a view of the receptacles and the frames in which they are arranged or held while in use, so as to completely utilize the room in a refrigerator.

A B C are three sections which compose the body of this refrigerator, showing at a glance that it may be made and used in one, two, or more parts, as desirable.

a a' are the outer and inner walls, made of sheet metal or other suitable material.

a² are the ring-flanges by which the outer and inner walls are closed air-tight by means of bolts, soldering, or otherwise hermetically sealed to render the space air-tight.

a³ is the bottom, constructed with two thicknesses, impervious to air.

a⁴ are doors fitted closely to their respective openings, constructed hollow, of sheet metal or other suitable material, and hung in the usual way.

a⁵ is a cover, also constructed hollow, of metal or other suitable material, and so that it will fit the upper end of either of the sections. Through the center of this cover is provided a vent orifice or tube, c. The only object of this vent-tube is to ventilate the box or receptacle when the freezing material is exhausted. Upon the inner wall of the sections are arranged rollers or brackets d, upon which the frames d' are supported and rotate, as desirable, either to the right or left, in order to bring any one of the receptacles placed therein directly before the door-openings. These receptacles e are made of porcelain, earthen, or metal material, and of the proper shape to utilize the room, as shown in Fig. 2. They (the sides or bottom) are made whole or perforated, as desirable, for the various articles which it may be desirable to place in them.

D is an ice-receptacle arranged in the upper portion of a refrigerator, composed wholly of metal or other suitable material, the body h of which is perforated and united to a tight bottom, i, slightly conical in shape.

h h' are flues which pass through the bottom i and the rim i' at the top of the box or receptacle, inside of which flues are arranged radial partitions, i'' to increase the cooling and condensing surface.

m is a cover which closes the top or opening

of the ice-box, thereby rendering it air-tight. The outside or perforated body of this receptacle is covered with a fibrous material, n, or other evaporating material, for the purpose of cooling, desiccating, or drying the air by internal continuous circulation without coming in contact with the ice. The product of condensation passes down into the chamber or flow k', thence through the discharge-tube o.

p is a fluid-cup, which receives the drip from the lower edge of the evaporating-surface and discharges the surplus fluid through a tube, o', near the upper edge of the cup, into the discharge-tube o'' arranged between the walls of the refrigerator. This ice-box is supported in its proper place and position by means of proper brackets or projecting arms g.

For producing circulating currents of cool dry air in this refrigerator by means of ventilation, the introduction of the air directly upon the ice is entirely unnecessary. Both produce extravagant use of ice for producing the results of refrigeration and desiccation. In this refrigerator is produced moving currents of cool dry air by effective means—i. e., by a result of evaporation of fluid or fluids separately or in combination with ice. This cooling-receptacle is so constructed that it occupies the upper section of the refrigerator. In fact, it is made movable and adjustable, and is constructed with a cylindrical flue or a series of cylindrical flues extending vertically from the top of the cooling-chamber, intersecting into a horizontal flue covering or extending across the bottom of the cooling-chamber, with an exit-opening in the center for the discharge of the cooling or circulating currents of air into the refrigerating-chambers below. Within the vertical flues are placed radial conductors that materially increase and extend the cooling and condensing surface of the receptacle.

The operation of this refrigerator is substantially as follows: When water or other evaporating fluid placed within the frigorific chamber finds its way into the evaporating-cup p the evaporating material instantly absorbs the fluid and extends itself to the top of the absorbing material. The warm air at the top of this receptacle finds its way downward through the flues, in consequence of there being a difference in the temperature of the air surrounding the evaporating material and the flues which are surrounded by the evaporating or absorbing material, which must be cooler within the receptacle than upon its exterior. Consequently a current of air is produced, passing through exit of the horizontal flue and falling directly through the center of the refrigerator-sections below. As a denser air, falling through an orifice, creates a displacement of air that may be before it, causing the same to arise, and in its gradual expansion passing in its upward circulation in close proximity with the absorbing and evaporating surface, it imbibes therefrom moisture in quantity wholly in accordance to its expansion and affinity therefor; and in its further circulation downward through

the flues again the moisture that is absorbed is wholly condensed within the flues and upon the radial conductors, and the atmosphere is freed, as it were, of the moisture it has imbibed from the evaporating-surface. By this means the effectual separation, by condensation of moisture from the air takes place, and the air becomes dry, and, in its circulation again downward through the center of the refrigerator-chambers, again coming in contact with the provisions and fruits, it absorbs therefrom moisture in its upward circulation. It follows close by the inner circumference form of the refrigerator in its ascent, and the air is continually expanding and still increasing its capacity for moisture until it again reaches the evaporating or absorbing surface, and taking therefrom, by absorption, the moisture and causing within the receptacle a cooling effect. Thus by this means I fully establish a result of internal continuous circulation of cool dry air.

When ice is introduced into the cooling-receptacle a great and important result is produced in economy in the use thereof, for, in combination with the evaporating-surface, it produces an effective cold, and a thorough ventilation of the ice is secured, removing the vapors necessarily generated by the ice being confined in an air-tight chamber by means of the exterior absorption.

I believe I have thus shown the nature, construction, and operation of this invention so as to enable others skilled in the art to make and use the same therefrom.

What I claim, therefore, and desire to secure by Letters Patent, is—

1. A refrigerator constructed of metal or other suitable material of two or more sections, substantially as and for the purpose described.
2. Diminishing the interior capacity of a refrigerator-chamber by dividing, cutting off, or removing a portion thereof, for the purpose of economizing in the use of the cooling agent, substantially as described.
3. The movable and adjustable frame d' , conforming to the interior shape of the refrigerator, with the receptacles e so formed that they fully utilize the interior capacity thereof, substantially as and for the purpose described.
4. An ice-box having a close bottom, perforated sides covered with absorbing fibrous material, whereby the box is rendered air-tight, substantially as described.
5. An ice-box, as above described, provided with a flue or series of flues, with or without radial divisions, for the circulation and condensation of air, substantially as described.
6. An ice-box, as above described, provided with a flue or series of flues, with or without perforated sides or evaporating-surface, substantially as described.
